UNITED STATES PATENT OFFICE

2,410,975

DISPLAY DEVICE

Job Hutchinson, Great Neck, N. Y., assignor to
Morris Pouzzner, Boston, Mass.

Application May 8, 1943, Serial No. 486,197

5 Claims. (Cl. 40—84)

1

This invention relates to a display apparatus or machine whereby a plurality of displays, such as curtain or sheet signs and the like, containing advertising matter of various kinds, are severally and successively displayed and each for a predetermined period of time.

More particularly, the invention relates to a display apparatus or machine of the character disclosed in United States Patents No. 2,190,426 of February 13, 1940, and No. 2,195,249 of March 26, 1940, granted to me.

It is an object of the present invention to provide improvements in machines and devices of the indicated character whereby various advantages in general construction and operation are attained.

Another object of these improvements is to simplify the general assembly, adjustments, and to increase the display area by eliminating unnecessary parts.

A further object of the invention is to provide improvements whereby a sign unit may be removed and replaced easily and quickly.

With these and other objects in view the invention consists of the provision, construction and operation of the parts hereinafter fully described and illustrated in the accompanying drawings, in which—

Fig. 1 is a front view of an apparatus embodying the features of the invention, the front part of the casing being removed, and certain of the sign units being omitted for the sake of clearness.

Fig. 2 is an enlarged sectional view taken approximately on the line 2—2 of Fig. 1 and looking in the direction indicated by the arrows, portions being broken away.

Fig. 3 is a vertical section showing the left side assembly together with a plurality of sign units, there being one sign unit on its way up, thus indicating how one sign member or sheet is unwound to be displayed while another is being rewound out of display.

Fig. 4 is an enlarged front view partly in section with parts broken away showing the driving and control mechanisms and one sign roller in section.

Fig. 5 is a sectional view taken on the line 5—5 of Fig. 4 showing the means for dogging or temporarily holding a sign unit in its up position.

Fig. 6 is an enlarged view of the left-hand ends of two carriers of respective sign units with the sign members or sheets partly unrolled.

Fig. 7 is a sectional view taken on the line 7—7 of Fig. 6.

2

Referring now to Figs. 1 and 3, it will be apparent the apparatus or machine includes a casing structure 10 consisting of two similar side plates 11 which form the side walls, a top wall 12, bottom wall 13, back wall 14 and front wall 15 having a sight or window opening 16 therein. The walls 12—15 are attached to the side plates in any suitable manner. A support or shelf 17 in the form of a channel is disposed horizontally between the side plates 11 in spaced relation to the top wall 12, and the opposite ends of the shelf 17 are rigidly secured to bosses on the plates 11, as at 18. Another support or shelf 19 of channel construction is disposed horizontally between the plates 11 in spaced relation to the bottom wall 13, and the opposite ends of the shelf 19 are rigidly secured to bosses on the plates 11, as at 20, and rest on flanges 21 on the plates 11 respectively.

20 The driving power is derived by an electric back geared motor 22 mounted on the shelf 19 near the left side of the casing. A driven shaft 23 is adjustably mounted on the shelf 19 beneath the same by means as follows. Lugs 24 depend from the shelf 19 in spaced relation. Bearing elements 25 are pivotally connected at one end with the lugs 24 respectively, as at 26. A hanger 27 for each bearing element 25 is adjustably connected with the shelf 19, and its lower end is pivotally connected, as at 28 with a lug 29 integral with the element 25. The shaft 23 projects through and is supported for rotation by the elements 25. Sprockets 30 and 31 are fast on the motor shaft and shaft 23 respectively. A driving chain 32 encircles the sprockets 30 and 31. The shelf has openings to pass the chain 32. The shaft 23 is adjustably mounted with respect to the motor shaft by virtue of the hangers 27 and this enables the proper tension to be placed on the chain 32. The shaft 23 provides a power transmission for operating the mechanism which effects the movement in part of the sign units 35 along a prescribed path for the intended purpose.

It is to be understood that any suitable number 45 of units 35 may be used and in some of the views of the drawing only a sufficient number of the units are shown to make the operation clear. These units 35 are identical in construction and operation and a description of one will suffice for all. A unit consists of a carrier 36 and a spring roller 37 on which is wound or rolled and from which is unwound or unrolled a sign member, curtain or sheet 38. The carrier 36 comprises a shaft 39 and bolsters 40 fast on the opposite ends 50 respectively of the shaft. Each bolster 40 carries

a pair of guide rollers 41, and has a lug 42 extending radially with respect to the axis of the shaft 39. Thus there are two lugs 42 for each carrier 36 and the purpose thereof will be explained hereinafter. The roller 37 is of the shade roller type but without a ratchet and its spring 43 serves for rewinding or rerolling the sign member thereon and is put under tension when the sign member is unwound. The sign member in the form of a curtain, web or sheet may be made of any suitable translucent material, such for instance, as stout paper, cloth, or other flexible sheet material on which may be imprinted or otherwise applied advertising matter of various kinds. The roller 37 is held against axial movement by the bolsters 40 each of which provides a cylindrical portion 44.

The sign units 35 have guided movement by virtue of a closed loop guideway 45 on each of the side plates 11. Each guide way is formed by spaced parallel flanges 46 integral with its plate 11 to provide traction surfaces for the rollers 41. The guideway consists of two straight runs 47 and 48 respectively joined by semi-circular ends 49 and 50 respectively. The two pairs of rollers 41 of each carrier 36 travel in the guideways 45 respectively and these rollers have a sufficient clearance with respect to the flanges 46 as not to bind or cause the carriers to be hung.

In order to move the sign units 35 successively one at a time along the lower semi-circular end 50 of the guideway from the straight run 48 to the front straight run 47, there is provided means as follows. A worm 51 fast on the shaft 23 meshes with a gear 52 fast on a stub shaft 53 supported for rotation by a bearing 54 secured to and depending from the shelf 19, there being a collar 55 on the upper end of the shaft 53, which in conjunction with the gear 52, hold the shaft 53 in place. A bevel gear 56 fast on the lower end of the shaft 52 meshes with a larger bevel gear 57 fast on a shaft 58 horizontally disposed below the shaft 23. The opposite ends of the shaft 58 are journaled in bearings on the side plates 11 respectively. The shaft 58 has its axis disposed coincident with the center from which the semi-circular portion of the guideway is struck. A pair of similar disks 59 are fast on the shaft 58 in proximity to the plates 11. Each of the disks has a plurality of notches 60 in the periphery thereof, there being ten notches 60 in the present instance in keeping with the size and number of the sign units 35 used. The notches 60 in the disks 59 cooperate with the portions 44 of the carriers 36 as the units 35 are presented by gravity one at a time from the guideway run 46 and transfer the units 35 to a point where they are picked up one at a time by means presently to be described.

The pick-up means comprises a shaft 61 adjustably mounted on the shelf 17 above the same by means similar to that which supports the shaft 23; therefore, similar reference numerals will be applied to corresponding parts. The lugs 24 and parts 27 applied to shaft 61 are the reverse of the ones applied to the shaft 23. Sprockets 62 are fast on the shafts 23 and 61 and they are arranged in pairs, there being one pair at each side of the sight opening 16 and in proximity to the guideways 45. A chain 63 encircles the sprockets 62 of each pair. Each chain 63 has a special link which is provided with a lug or abutment 64 having an anti-friction roller, as shown in Figs. 2, 3 and 5. In each cycle of the chains 63 the disks 59 move one-tenth of a revolution, 75

so that in timed accord the lugs 64 will engage the carrier portions respectively of a sign unit 35 and cause the latter to move upwardly of the casing 10 at the window 16 as indicated in Figs. 2 and 3. This operation is repeated on each sign unit 35. The shelves 17 and 19 have openings to pass the chains and their lugs.

In order to cause the display of the sign member or sheet 38 of each unit 35 by unrolling the member, prior to the upward travel of the unit, the member or sheet 38 has a pull-rod 65 extending through a tunnel on the outer end thereof. The opposite ends of the rod 65 are threaded as at 66 and each of said ends carries a thumb nut 67 or the like. The ends of the pull-rod 65 are received in notches 68 respectively of the lugs 42 of the carrier 36 of the next preceding sign unit. The nuts 67 when tightened against the lugs 42 hold the rod 65 in place and the related sign member 38 connected for the unwinding or rewinding operation as may be the case. See Figs. 6 and 7.

Attention is called to the fact that the provision of the lugs 42, pull-rod 65 and nuts 67 for each sign unit 35 enables a unit to be readily removed and replaced whenever desired, easily and quickly. In this respect it is to be noted the nuts 67 may be loosened and the rod 65 disengaged from the lugs 42. The unit 35 in its entirety then may be canted or have one end raised slightly above the other end to remove the unit from the guideways 45. A unit 35 may be replaced in a reverse manner.

As each unit 35 is brought to its up position 35 it is temporarily held therein for a predetermined period of time by a back-check means at each side of the opening 16. Said means consists of a pawl or check member 69 pivotally mounted on the shaft 61 and kept in operative position by a collar 40 70 fixed on the shaft and the adjacent sprocket 62. A contractile coil spring 71 has one end connected with the lower end of the pawl 69, as at 72, and the opposite end connected with a set screw 73 carried by a lug on the shelf 17. An upstanding stop 74 on the shelf 17 limits the movement of the pawl 69 against the action of the spring 71 to its checking position as shown most clearly in Fig. 5. The pawls or check members 69 cooperate with the carrier portions 44 respectively of each unit 35. As the unit moves upwardly the portions 44 cam the pawls 69 against the action of the springs 71 to clear the same, after which, under the reaction of the springs, the upper ends of the pawls reengage the portions 44, thereby checking the unit in the up position just as the lugs 64 clear the same.

As each of the units 35 reaches its up position it crowds the preceding units by reason of the contact of the guide rollers 41. This causes the units to traverse the upper curved ends 49 under power transmitted by the chains 63 and their lugs 64 until the units 35 reach the down sides of said ends 49, whereupon the units drop by gravity into the vertical runs 48 of the guideways.

From the foregoing it will be obvious that the slow rotation of the disks 59 causes the units 35 to be presented successively one at a time to the lugs 64 which move each unit upwardly until engaged by the back-check means 69. As a unit 35 is retained in its up position by the means 69, a second unit is being moved upwardly by the lugs 64, a third unit will be held in its down position by the disks 59 all directly behind the sight opening 16 as indicated in Fig. 3. Consequently, the sign member 38 of said second unit will be

rewound as the sign member 38 of said third unit is being unwound. Thus one sign member is being rewound as one is being unwound and this action takes place after a sign member has been displayed for a predetermined period of time.

Attention is called to the fact that by adjustably mounting the shafts 23 and 61, the chains 63 will be kept adjusted to bring their lugs 64 around at the proper time and so keep the units 35 moving periodically as required. Also the chain 32 may be adjusted slightly if necessary.

The shelves 17 and 19 serve adequately for supporting reflectors or mirrors 15 and also lighting elements such as the fluorescent tubes 16 in front of the reflectors. Thus provision is made for illuminating the sign members or sheets 38 as they are displayed. Any suitable source of voltage may be coupled to the lamps and motor.

I claim:

1. In a display sign, carriers having guided movement and each having a spring actuated sign sheet roller operatively mounted thereon, spaced lugs on each carrier between which the outer end of the sign sheet on the next succeeding carrier may be disposed, and means on said 20 outer end to detachably engage the last mentioned sheet with said lugs, said means consisting of a pull rod on said outer end of the indicated sign sheet, and clamping members on said rod and engaged with said lugs.

2. In a display sign, carriers having guided movement and each having a spring actuated sign sheet roller operatively mounted thereon, spaced lugs on each carrier between which the outer end of the sign sheet on the next succeeding carrier may be disposed, and means on said 25

outer end to detachably engage the last mentioned sheet with said lugs, said means consisting of a pull rod on said outer end of the indicated sign sheet, the opposite ends of said rod being threaded, clamping nuts on the threaded rod ends respectively, said lugs having provision to receive the rod ends respectively, and said nuts being clampingly engageable with said lugs.

3. In a sign display device in which sign units 10 are caused to travel in a prescribed path to display the signs of said units successively, means to move said sign units one at a time a predetermined distance, said means including a horizontal shaft; and back-check means including pawls 15 operatively mounted on said shaft engageable with each sign unit presented thereto to temporarily hold it in the position it has been moved into by said first means.

4. In a sign display device in which sign units are caused to travel in a prescribed path to display the signs of said units successively, pick-up 20 means to move said sign units one at a time a predetermined distance, said pick-up means including a shaft and adjustable means supporting said shaft; and back-check means including pawls pivotally mounted on said shaft engageable with each sign unit presented thereto to temporarily hold it in the position it has been moved into by said pick-up means.

5. In a sign display device as set forth in claim 30 3, wherein said back-check means also includes stops to limit the movement of the pawls respectively to the checking position, and springs to move said pawls respectively into the checking 35 position.

JOB HUTCHINSON.
